CLAIM

The ornamental design for a strength training dip stand, as shown and described.

DESCRIPTION

FIG. 1 is a front, right and top perspective view of a strength training dip stand, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is a partial enlarged view of an area labeled 9 in FIG. 1.

FIG. 10 is a partial enlarged view of an area labeled 10 in FIG. 1.

FIG. 11 is a partial enlarged view of an area labeled 11 in FIG. 1.

FIG. 12 is a partial enlarged view of an area labeled 12 in FIG. 3.

FIG. 13 is another perspective view of a strength training dip stand in an alternative state; and,

FIG. 14 is another perspective view of a strength training dip stand in a second alternative state.

The broken lines shown in the drawings are included for the purpose of illustrating portions of the strength training dip stand that form no part of the claimed design. Dot-dash broken lines framing portions of the claimed design that are illustrated for enlargements form no part of the claimed design.

1 Claim, 14 Drawing Sheets
